JOHN AUGSPURGER, OF TRENTON, OHIO.

Letters Patent No. 63,826, dated April 16, 1867.

IMPROVEMENT IN PORTABLE FENCE.

The Schedule referred to in these Letters Patent and making part of the same.

TO WHOM IT MAY CONCERN:

Be it known that I, JOHN AUGSPURGER, of Trenton, Butler county, Ohio, have invented a new and useful Improvement in Portable Fences; and I do hereby declare the following to be a full, clear, and exact description thereof, reference being had to the accompanying drawings, making part of this specification.

My invention relates to a light, portable fence, easily moved from place to place, and quickly set up and connected where desired without the labor of digging post-holes, at the same time that it makes a firm fence, and cannot be lifted or disconnected by swine to get under, nor pushed over by cattle, nor easily blown down by the wind, but may be quickly and easily separated and removed by the proprietor when desirable.

The drawing represents a portion of two panels as set up, showing the mode of connecting them.

I construct my fence in panels as light as consistent with proper strength, consisting of two posts of unequal lengths, A and B, connected by a suitable number of rails, (preferably five,) with a brace either diagonal or vertical about the mid-length of the panel. The post A at one end of each panel is only of sufficient length for the attachment of the rails, but the other, B, is longer, leaving a foot to support the panel above the ground of such length as may be necessary, one foot being thus furnished at each joint. The top, bottom, and centre rails, (more or less,) of each panel extend at each end beyond the posts, and are gained out for half their width, the gains F F being in the upper side at one end and the lower side at the other, and the panels are connected by engaging the gains of one panel in the corresponding ones of the next, as shown. At G is shown an arrangement of gains for the purpose of attaching a cross fence, shown in dotted lines. Cleats secured over the rails at one post B, and the brace C of each alternate panel, retain in position a short length of rail, D, which slides back and forth under the top rail, and the panels being connected by means of the gains this slide D is protruded under the joint, thereby preventing the raising of the upper panel to disconnect them. A stop or peg, E, regulates, by its impact against the post B, the extent of motion of the slide. The panels are set upon the ground in a worm or zigzag form so that each panel thus serves as a brace for those adjacent, securing the firmness and rigidity of the fence.

I claim herein as new, and of my invention—

The construction of a light, portable fence in lengths or panels, with one short and one long post, substantially as shown and described, to be connected and secured in a worm or zigzag form by means of the prolonged and gained rails F F', in combination with the slide D, as shown and set forth.

In testimony of which invention I hereunto set my hand.

JOHN AUGSPURGER.
